MORTAR OR CANNON AND PROJECTILE ADAPTED FOR USE THEREWITH.

1,307,384.

Specification of Letters Patent. Patented June 24, 1919.

Application filed August 23, 1917. Serial No. 187,861.

To all whom it may concern:

Be it known that we, PIERRE VAN DEUREN, ALBERT DELAS, and MAURICE LEBLANC, the first a subject of the Kingdom of Belgium, residing in Calais, France, the others citizens of the Republic of France, residing in Paris, France, have made a new and useful Invention in Mortars or Cannon and Projectiles Adapted for Use Therewith, of which the following is a specification.

This invention relates to mortars or cannon and projectiles adapted for use therewith and has particular reference to the means for setting the range.

15 In a general way the cannon or mortar consists of a smooth bore barrel mounted at an angle of approximately 45° to the horizon. The projectile consists of a head or body containing the explosive charge and has 20 a hollow tubular tail secured thereto and which contains the propelling charge. Radially extending rings for guiding the projectile in flight are secured to the body.

An object of this invention is to provide 25 a combined cannon and projectile capable of being fired in all directions around the horizon with a constant elevation angle of approximately 45° and in which the variation in range is primarily obtained by regulating the volumetric capacity of the explosion chamber formed by the cannon bore and the hollow tail of the projectile.

A further object is to provide a method whereby, with a given angle of elevation 35 and a given explosive propelling charge, different ranges may be set by varying the length and therefore the volumetric capacity of the explosion chamber containing said charge.

40 These, as well as other objects, we attain in the device described in the specification and illustrated in the single sheet of drawings accompanying and forming a part of this application.

45 In the drawings Figure 1 is a view in sectional elevation of a cannon or mortar and a projectile embodying this invention and Fig. 2 is a view in cross section, taken on line 2—2 of Fig. 1, looking in the direction of the arrows.

Referring to Fig. 1 the cannon proper consists of a barrel 1 secured in a socket member 2 by means of a set screw 3. Socket

member 2 is mounted upon a base 4 and is provided with a central circular chamber 5 within which a circular boss 6 formed on the base co-operates to form a vertical axis about which the cannon may be turned 360°.

Base 4 is mounted on a suitable platform 7 and the barrel has a smooth bore 8 and is fixed at a constant elevation angle of approximately 45°. The elevation angle of 45° has the advantage of giving the maximum range and this is not appreciably affected by a variation in the angle of 5° above or below. It has been found that the platform may incline 5° either above or below the normal position of 45° angle without influencing the maximum range and this is especially important not only in trench warfare where the ground is often bad and the platform liable to move but is important in firing at sea as it has been found that the rolling or pitching of the ship has no influence upon the range when the elevation angle is normally 45°.

The projectile which forms part of this invention consists of a body or head portion 9 containing the explosive charge and to the body a tubular tail portion 10 is secured; the body is also provided with radially extending vanes or wings of any desired number above three.

Since the elevation angle of the cannon is constant and the powder for the propelling charge preferably constant the setting of the range is obtained by varying the distance or depth to which the tubular tail 10 enters the bore of the cannon. For the purpose of adjusting this depth a screw thread 11 is cut in the outer surface of the cannon and an internally threaded ring 12 movable on said threads serves as an abutment or stop against which the lower end of wings or vanes rest when the projectile is in properly adjusted position. By varying the distance between the bottom of the cannon bore and the upper inner end 13 of the hollow tail the volumetric capacity of the explosion chamber for the propelling charge is varied. When the tubular tail projects the maximum distance into the cannon bore the pressure exerted by the propelling charge of powder is high and the run of the tail in the bore long, thus giving the longest or maximum range to the projectile. On the other hand

when the abutment ring for the vanes is moved to a position allowing the tubular tail to extend only a slight distance into the cannon bore the explosion chamber for the propelling charge is large; the pressure relatively low and the possible run of the tail in the cannon bore short with a consequent short range. By means of the abutment ring the desired range may be quickly and accurately set by adjusting the ring lengthwise of the barrel in accordance with the range scale marked thereon for facilitating the adjustment.

10 The guide vanes which may be of any desired number above three serve to guide the projectile in the air and to maintain it upon its trajectory.

15 The tubular tail open at its lower end allows the cannon, the bore of which is of given length and diameter, to have an explosion chamber of maximum volumetric capacity and the use of the hollow tail provides an increase in the chamber equal to the space between the upper end of the tail 20 and the outer end thereof thus accommodating a larger quantity of powder while maintaining the same maximum pressure. The hollow tail has the further advantage that the pressure is exerted close to the center 25 of gravity of the projectile instead of against the outer end as would be the case if the tail were solid. This exertion of the pressure close to the center of gravity of the projectile gives better stability to the projectile in 30 the air. The hollow tail also gives us an explosion chamber for the propulsive charge part of which is located outside of the cannon bore thus allowing the wires for igniting the propulsive charge to enter the explosion 35 chamber at a point outside of the cannon bore through the small hole 14. For this

40 reason the cannon simply consists of a tube closed at its lower end and is without breach or firing apparatus thus adding materially to the solidity of the cannon and its simplicity.

45 The nature and scope of the invention having been thus indicated and its preferred embodiment having been specifically described, what is claimed as new is:

50 1. The combination with a cannon or mortar having a smooth bore, of a projectile having a head or body portion, a hollow tubular tail open at its outer end, guide vanes secured to the projectile and means 55 on said cannon coöperating with said vanes for limiting the distance to which said tail extends into the bore of the cannon.

55 2. The combination with a cannon arranged to discharge a projectile at a substantially constant angle, of a projectile consisting of a body portion, a hollow tubular tail secured to the body portion, and fitting within the bore of the cannon, radial guide vanes secured to the projectile, and means 60 on said cannon forming an abutment for said vanes for determining the volumetric capacity of the chamber for the propelling charge.

65 3. The combination with a cannon, of a projectile having a hollow tail fitting the cannon bore and, with said bore, forming the explosion chamber for the propelling charge, a body for said projectile secured to said tail and which is adapted to contain an explosive charge, wings for said projectile, and means coöperating with said wings for determining the distance to which said tail projects into the cannon bore.

70 PIERRE VAN DEUREN.

ALBERT DELAS.

MAURICE LEBLANC.
